UNITED STATES PATENT OFFICE.

MARY D. NEILSON, OF MINNEAPOLIS, MINNESOTA.

UNDERGARMENT FOR WOMEN.

1,389,067.

Specification of Letters Patent. Patented Aug. 30, 1921.

Application filed August 21, 1920. Serial No. 405,139.

To all whom it may concern:

Be it known that I, MARY D. NEILSON, a citizen of the United States, residing at Minneapolis, in the county of Hennepin and State of Minnesota, have invented certain new and useful Improvements in an Undergarment for Women, of which the following is a specification.

My invention relates to an undergarment for women, and has for its object to provide an undergarment with a closed crotch and an opening along the side of the leg which shall be adapted to have the legs closed to produce a bloomer construction, which shall be of inelastic material such as muslin or nainsook, which shall fit the wearer no matter what the position of the body without any strain or tension at any point, and which shall be particularly comfortable and satisfactory when worn. The garment of my invention which may be either a union garment comprising waist and leg portions or drawers-bloomers only, preferably has no waist opening but is adapted to slip up over the form of the wearer, there being only a side opening along one of the legs which is closed by snaps, buttons or other forms of fastening. Substantial fullness is produced by the combined effect of making the back portion of the garment longer in amount of material than the front portion and gathering the edges of the back portion to the edges of the front portion in combination with the provision of a rectangular insertion sewed directly to the center cleft edges of the front member and the curved bottom edge of the back member, whereby the two portions are united to form legs and at the same time provide a substantial depth of material at the crotch.

It is to be noted that the garment whether consisting of waist and drawers portions or drawers portion alone is composed of but three pieces, a back member, a front member and the aforesaid insert. The construction of the garment is made exceedingly simple by the fact that the front member is formed with a single slit or cleft at its center to which the insert is sewed directly, the same being in turn sewed to the bottom curved edge of the back member, whereby legs of substantial length are provided with a markedly fulled seat portion, and yet the garment will have a straight front closely fitting the form of the wearer.

The full objects and advantages of my in-

vention will more fully appear in connection with the detailed description thereof, and the novel features of the invention are particularly pointed out in the claims.

In the drawings illustrating the application of my invention in one form, Figure 1 is a perspective view of a figure wearing a garment formed of the drawers member only, and Fig. 2 is a figure wearing a somewhat similar union garment, both Fig. 1 and Fig. 2 showing the straight line front effect of the garment. Fig. 3 shows a figure in a distorted position wearing a union garment and showing the natural fit of the garment in the extreme position of the wearer. Figs. 4, 5 and 6 are pattern views of the three piece making up the union garment. Figs. 7, 8, and 9 are similar pattern views of three pieces making up the bloomer garment only.

As illustrated, a front member 10 is provided having slightly curved side edges 11 and 12 and a central bottom cleft 13. The back member 14 of greater length than the front member 10 is provided with curved side edges 15, 16 and a curved bottom edge 17, all as shown in Figs. 4 and 5. The front member 10 and back member 14 have portions *a* and *a'* at the side edges 11 and 12 which are of equal length and are sewed together to produce the waist of the union garment. Other portions of the edges 11, 12 and 15, 16 respectively, *b* and *b'* are sewed together, edge portion *b'* of back member 14 being of greater length than edge portions *b* of front member 10 so that the back member 15 is at these points fulled to the front member 10 as shown at 18 in Figs. 1 and 2 and also at 19 in Fig. 3, where the fulling is to a separate band 20 removably fastened by snaps or other suitable means to a band 21 on the front member 10. A similar combination of elements is shown in Figs. 7 and 8 for front member 21 and back member 22, except that in this instance the portions *a* and *a'*, respectively, are shorter and do not provide a waist portion but merely a band at the waist, the edges *b* being shorter than the edges *b'* producing the fulled effect, exactly as in the union garment of Figs. 4 and 5. The front member 21 has a central cleft or slit 23, exactly like the cleft 13 of the member 5. In fabricating the garment, a rectangular piece 24, as shown in Figs. 6 and 9, is sewed along its edge to the edges of the cleft 23 or 13, forming an insert as indicated at 25 in Fig. 1. The rear edge of the

insert 24 is sewed to the curved edge 17 of back member 14 or to similar curved edge 26 of back member 22. The leg openings are formed by the lower edges 28 and 29 of the 5 front members, the oblique edges 30 and 31 of the back members and the end edges 32 and 33 of the insert 24. These leg openings are preferably gathered together by an elastic band, as indicated at 35 in Figs. 1, 2 10 and 3.

The garment produced in the above manner has, as shown, a perfectly straight front with material depth at the crotch from the front to the back and substantial fullness at 15 the seat portion of the drawers member of the garment.

It will be noted that the provision of the insert attached along its edges to the cleft 13 gives to the front member increased width 20 of material extending inwardly from the lower portion of the median line of the front member, of which the cleft 13 is a geometrical continuation. That is, considering the front member 10, as shown in Fig. 25 5, extended in a plane and the strip 33 sewed along one edge to the edges of cleft 13 and folded at its center, it would have the effect of increasing the width of material of each portion at the side of the cleft 13 an amount 30 equal to the width of the insert 24 and this increase of width of material would be directly inward or backward from the cleft 13. It is this increase of width provided in this 35 manner at the point specified which gives a crotch fullness between the legs of the garment extending directly back from the lower end of the median line of the front member, and which in connection with the fulled union of the back member at its side edges 40 to the side edges of the front member produces seat fullness along lines spaced from the crotch center.

I claim:

1. A woman's undergarment comprising 45 a back member having the central portion of the bottom edge concavely curved throughout its length, a front member having its center cut along a straight line a predetermined distance, and an insert sewed along 50 one edge to the edges of said central cut and along another edge to the curved edge of the back member.

2. A woman's undergarment comprising 55 a back member having the central portion of the bottom edge concavely curved throughout its length, a front member having its center cut along a straight line a predetermined distance, and an elongated rectangular insert sewed along one longitudi-

nal edge to the edges of the center cut and 60 along another longitudinal edge to the curved edge of the back member.

3. A woman's undergarment comprising a front member having its center cut along a straight line a predetermined distance 65 and having side edges, a back member having the central portion of the bottom edge concavely curved throughout its length, and having side edges of greater length than the side edges of the front member, said side 70 edges of the back member having a fulled connection with the side edges of the front member so as to produce substantial fullness in the seat portion of the garment, and an insert sewed along one of its edges to the 75 edge of said center cut and along another of its edges to the curved edge of the back member.

4. A woman's undergarment comprising a front member having its center cut along a 80 straight line a predetermined distance and having side edges, a back member having the central portion of the bottom edge concavely curved throughout its length and having side edges of greater length than the 85 side edges of the front member, said side edges of the back member having a fulled connection with the side edges of the front member so as to produce substantial fullness in the seat portion of the garment, and an 90 insert having parallel edges, one of said parallel edges being sewed throughout its length to the edges of said center cut and the other of said parallel edges being sewed to the curved edge of the back member. 95

5. An undergarment comprising a back member having side edges and a bottom edge formed with a straight portion extending from and angularly disposed in relation to each of said side edges and having a portion 100 between the two straight portions concavely curved throughout its length, a front member having side edges connected with the side edges of the rear member and having increased width of material extending inwardly from the lower portion of the median line of said front member, said increased width of material having a continuous edge connected throughout its 105 length with the curved edge only of the back member, whereby leg members of the garment are formed with crotch fullness extending directly back from the median line 110 at the front of the crotch between said leg members.

In testimony whereof I hereunto affix my signature.

MARY D. NEILSON.
